13 Claims. (Cl. 260—429.7)

This invention relates to organotin dithiocarbamates and more particularly to the hydrocarbon isodithiocarbamates of general formula:

wherein R', R'' and R''' are the same or different and are hydrocarbon groups and n is an integer from 1 to 3.

The hydrocarbon isodithiocarbamates of the present invention also include compounds wherein, when n is 2 or 3 in the above formula, R' may represent different hydrocarbon radicals. For example, when n is equal to 2 in Formula 1, the hydrocarbon isodithiocarbamates of this invention may take the form:

wherein R, R', R'' and R''' are the same or different hydrocarbon radicals. Furthermore when n is equal to 3 in Formula 1, the compounds of this invention may take the form:

wherein R, R', R'', R''' and R''''' are the same or different hydrocarbon radicals.

In all the above formulas R, R', R'', R''' and R''''' may be any hydrocarbon radicals. They may be, for example, any alkyl radical such as methyl, ethyl, n-propyl, isopropyl, n-butyl, iso-butyl, tert-butyl, pentyl, hexyl, ethylhexyl, heptyl, octyl, nonyl, heptycyl, dodecyl, tridecyl, tetradecyl, pentadecyl, hexadecyl, etc. They may also represent any cycloalkyl radical such as cyclopropyl, cyclobutyl, cyclopentyl, cyclohexyl, cycloheptyl, etc. They may also represent any aryl, aralkyl or alkaryl hydrocarbon radical. Among these may be mentioned, phenyl, naphthyl, anthracyl, biphenyl, benzyl, phenyl-ethyl, tolyl, xylyl, xenyl, cinnamyl and methylbenzyl. They may also be any alkenyl, alkynyl or cycloalkenyl radical. Included in these are propenyl, butenyl, hexenyl, cyclopentenyl, butadienyl, cyclopentadienyl, cyclohexenyl as well as long chain unsaturated alkyl radicals derived from unsaturated fats.

The hydrocarbon isodithiocarbamates of the present invention are prepared by reacting an isodithiocarbamic acid with a hydrocarbon compound having a readily replaceable functional group bonded to tin. Hydrocarbon reactants of particular utility are the hydrocarbon oxides. The intermediate isodithiocarbamic acid may be made by reacting a primary amine with carbon disulfide and a metal hydroxide, preferably an alkali metal hydroxide, and then reacting the metal dithiocarbamate,

2

so formed, with an organic halide. The synthesis may be illustrated as follows:

It is to be understood, however, that this invention is not restricted to the particular method of forming the isodithiocarbamic acid which has been illustrated in these equations.

20 Hydrocarbon halides may be substituted for the hydrocarbon oxides in the above sequence of reactions. In this process, the reaction between the isodithiocarbamic acid and the hydrocarbon halides may be described by the following equations:

In Equations 4, 5, 6 and 7 R, R' and R'' have the same significance ascribed to them above and X is a halide, such as, chloride.

In the hydrocarbon reactants in Reactions 4 to 7 above the hydrocarbon radicals may be the same or different. The following reactions illustrate the case wherein the hydrocarbon reactant contains different hydrocarbon groups:

In which R, R', R'', R''' and R''''' are hydrocarbon radicals and X is a halide like chloride.

Likewise, in Reactions 4 to 11 the hydrocarbon radicals of the isodithiocarbamic acid reactant may be the same or different from each other.

65 Among the hydrocarbon oxide reactants that may be used in the process of the present invention, illustrated in Equations 4 and 8, may be mentioned dimethyltin oxide, diethyltin oxide, dipropyltin oxide, di-n-butyltin oxide, di-isobutyltin oxide, di-isoamyltin oxide and di-phenyltin oxide. The preferred organotin oxide reactants are dimethyltin oxide and di-n-butyltin oxide. Included in the hydrocarbon halide reactants that can be used

in the process of this invention, as illustrated in Equations 5 to 7 and 9 to 11, are: dimethyltin dichloride, diethyltin dichloride, ethyl n-propyltin dichloride, di-n-propyltin dichloride, di-tert-butyltin dichloride, di-isobutyltin dichloride, di-isoamyltin dichloride, di-tert-amyltin dichloride, trimethyltin chloride, triethyltin chloride, tri-n-butyltin chloride, tri-isobutyltin chloride, tri-tert-butyltin chloride, tri-isoamyltin chloride, diethyl-n-propyltin chloride, diethyl-n-amyltin chloride, methyltin trichloride, triphenyltin chloride, tri-p-tolyltin chloride, tri-m-tolyltin chloride, trio-o-tolyltin chloride, tri-2,5-xylytin chloride, tri- β -naphthyltin chloride, tri-benzyltin chloride, tri-cyclohexyltin chloride, diphenyltin dichloride, di-o-tolyltin dichloride, di-p-tolyltin dichloride, phenylethyltin dichloride, dibenzyltin dichloride, di-cyclohexyltin dichloride, phenyltin trichloride, o-tolyltin trichloride, p-tolyltin trichloride.

In the preparation of the intermediates used in this invention according to Reaction 4, any primary amine may be used. These include primary alkyl amines such as, for example those having from 1 to 18 carbon atoms per alkyl group which include: methylamine, ethylamine, n-propylamine, isopropylamine, n-butylamine, tert-butylamine, pentylamine, hexylamine, heptylamine, octylamine, nonylamine, decylamine, hendecylamine, tri-decylamine, tetradecylamine, pentadecylamine, hexadecylamine, ethylhexylamine. The preferred primary alkyl amine is butylamine. Alkenyl and alkynyl amines may also be used in Reaction 4 above. These include propenyl amine, butenyl amines, hexenyl amines, butadienyl amines as well as amines having long chain unsaturated alkyl radicals derived from unsaturated fats.

Primary saturated and unsaturated cycloalkyl amines, arylamines, aralkylamines are also useful in Reaction 4. Among these may be mentioned cyclopropylamine, cyclobutylamine, cyclohexylamine, cyclopentylamine, cyclohexenylamine, aniline, β -naphthylamine, phenylethylamine, benzylamine, p-tolylamine, anthracylamine, biphenylamine, o-tolylamine, xylylamines, xenylamines, cinnamylamine and methylbenzylamine. Among the preferred amines in this grouping are cyclohexylamine, aniline and benzylamine.

As noted above the intermediate isodithiocarbamic acids are prepared by the reacting the metal salt of the dithiocarbamic acid with an organic halide. Any organic halide may be used, for example, in Reaction 4 above. Included among these are the alkyl chlorides, for example, those having from 1 to 18 carbon atoms per alkyl radical which include methyl chloride, ethyl chloride, n-propyl chloride, isopropyl chloride, n-butyl chloride, tert-butyl chloride, pentyl chloride, hexyl chloride, heptyl chloride, octyl chloride, nonyl chloride, decyl chloride, pentadecyl chloride, tridecyl chloride, tetradecyl chloride, hexadecyl chloride, ethylhexyl chloride. Saturated and unsaturated cycloalkyl chlorides, aryl chlorides and aralkyl chlorides may also be used in Reaction 4. Among these may be mentioned cyclopropyl chloride, cyclobutyl chloride, cyclohexyl chloride, cyclopentyl chloride, cyclohexenyl chlorides, chlorobenzene, chloronaphthalene, phenylethyl chloride, benzyl chloride, p-tolyl chloride, chloroanthracene, biphenyl chlorides, o-tolyl chloride, xylyl chlorides, xenyl chloride, cinnamyl chloride, methylbenzyl chlorides. Alkenyl and alkynyl chlorides may also be used in Reaction 4 above. These include propenyl chloride, butenyl chlorides, hexenyl chlorides, butadienyl chlorides as well as long chain unsaturated alkyl radicals derived from unsaturated fats.

The reaction conditions for the preparation of the organotin isodithiocarbamates of the present invention vary with the particular isodithiocarbamic acid made or employed and the particular organotin reactant selected. In general the organotin isodithiocarbamates are made according to the present invention by the reaction of the isodithiocarbamic acid with the organotin reactant at a temperature between room temperature and about 150° 75

C. Preferably the reaction is carried out at an elevated temperature between about 60° C. and 135° C.

The manner in which the product is recovered is dependent on the physical state of the product. When the products are liquid they may be separated from the reaction mixture by a separatory funnel and then stripped of solvent.

The following examples are further illustrative of the present invention. It is to be understood, however, that the present invention is not restricted thereto.

EXAMPLE 1

Dimethyltin bis (N-butyl S'-benzylisodithiocarbamate)

A 2000 ml. 3 neck reaction flask was equipped with a stainless steel anchor stirrer, a "Glas-Coil" heating jacket, a 3 way adapter with a reflux condenser and dropping funnel. A pot thermometer was located in off center adapter. A mixture of 73.0 gms. (1.0 mole) of butylamine and 41.0 gms. (1.0 mole) of NaOH (Bakers, pellets 98.2%) in 250 ml. of H₂O was charged into the flask. 76.0 gms (1.0 mole) of CS₂ was slowly added to the flask and the temperature rose immediately. 40 minutes after start the temperature was 58° C. and the addition of the CS₂ was completed. The mix appeared as a fairly clear orange solution.

The reaction mixture was allowed to stand overnight. The next morning it appeared as an orange liquid with some solid crystalline material on its surface. The heater was turned on (30 v.) as well as the stirring and 126.5 gm. (1.0 mole) benzyl chloride was slowly added. The addition of the benzyl chloride was completed in 1 hour and the pot temperature at this time was 78° C. The reaction mix now had a yellow color. The reaction was continued for another 4 hours and then the heat was turned off and the reaction mixture cooled to a temperature of about 60° C. Two layers appeared, an oil layer and an aqueous layer. These layers were separated. The oil layer weighed 239.2 gms. It contained a slight amount of water. (Theory at this point=239.0 gms.) This product was placed in a covered beaker and allowed to stand overnight. The next day this product was again charged into the flask of the set up. 82.3 gm. (0.5 mole) of dimethyltin oxide and 200 ml. of toluene was added to the flask. The heater was set at 50 v. and the stirrer was turned on. The reaction was allowed to proceed for two hours and 10 minutes and the heater was turned off. 110 ml. of H₂O were removed from the reaction mix. The reaction mixture was allowed to stand in the set about two days. The heater and stirrer were then again turned on. A yellow solid was dispersed through the reaction mix. The reaction was allowed to proceed about another 7 hours and then heater was turned off. The reaction mix was allowed to stand over night. The next day it was filtered under suction. 20.7 gms. of a white precipitate and a light brown filtrate were obtained.

Filtrate was stripped by vacuum distillation to a pot temperature of 120° C. and at 5 mm. of mercury. The product is a light brown liquid which weighed 211.7 gms.

60 Analysis:

Theoretical mol. wt.=624.7

Theoretical Sn=19.0%

Theoretical Sulfur=20.5%

The reaction sequence may be described as follows:

EXAMPLE 2

Dibutyltin bis S(N-benzyl-S' benzyl isodithiocarbamate)

Using the same apparatus described in Example 1, a mixture of 73.9 gms. (1.9 mole) of benzylamine and 41.0 gms. (1.0 mole) of NaOH (Bakers, pellets 98.2%) in 200 ml. of H_2O was charged into the flask. 76.0 gms. of CS_2 was slowly added to the flask.

At start the pot temperature was 38° C . The temperature immediately rose and there was a pink coloration in the reaction mix. Five minutes after start the temperature was 47° C . and the mix appeared as a cloudy solution. One minute after that the pot temperature was 50° C . and the mix appeared as a clear orange solution. Four minutes later the pot temperature was 55° C . and some refluxing started. The mix appeared as a cloudy organic solution containing dispersed solids. The addition of CS_2 was complete 20 minutes after start. The temperature at this time was 50° C . This reaction was continued for another 20 minutes at which time the pot temperature was 42° C . Addition of 126.5 gms. (1.0 mole) of benzyl chloride was then begun. This was completed in 25 minutes at which time the pot temperature was 56° C . The heat was then turned on (40 v.). 10 minutes after the heat was turned on the temperature was 66° C . and the reaction mix had a yellow color. Heating was continued for another 30 minutes and then the heater was turned off. The reaction mix was allowed to stand for about 10 minutes and then poured into a separatory funnel. 235.1 gms. of the light brown viscous oil was recovered (86.2% of theory). This oil was returned to the reaction flask. 124.4 gms. (0.5 mole) of dibutyltin oxide and 200 ml. of toluene were then added to the flask and heat applied. 30 minutes after this addition the temperature was 103° C . Some foam appeared in the reaction mix and it had a yellow color. 2 ml. of H_2O were removed from the mix. 5 minutes later the pot temperature was 112° C . The dibutyltin oxide had dissolved and 4.0 ml. of H_2O were removed. The reaction was continued for another 25 minutes at which time the pot temperature was 123° C . 6.0 ml. of H_2O were removed from the reaction mix. The heat was then turned off. The reaction mixture was allowed to stand about 3 days and then a white solid was removed by filtration under suction. This had a dry weight of 63.8 grams. The filtrate was stripped by vacuum distillation to 125° C . at 10 mm. of mercury. Residue was a light brown liquid. Weight=274.6 grams.

Analysis:

Precipitate—

 $\text{Sn}=1.05\%$ $\text{Sulfur (comb.)}=11.80\%$

Residue—

 $\text{Sn}=21.23\%$ $\text{Sulfur (comb.)}=16.67\%$

Theoretical mol. wt.=776.7

Theoretical Sn=15.3%

Theoretical sulfur=16.5%

The reaction sequence may be described by the following:

EXAMPLE 3

Dibutyltin bis S(N-cyclohexyl S'-benzyl isothiocarbamate)

Using the apparatus described in Example 1, a mixture of 99.2 gms. (1.0 mole) of cyclohexylamine and 41.0 gms. (1.0 mole) of NaOH (Bakers, pellets 98.2%) in 200 ml. of H_2O was charged into the flask. 76.0 gms. (1.0 mole) of CS_2 was slowly added to the flask.

The initial pot temperature was 35° C . The reaction was exothermic and there was an immediate rise in temperature. Three minutes after start the pot temperature was 40° C . and the mix had a cloudy pink color. Ten minutes later $\frac{1}{2}$ of the CS_2 had been added. The pot temperature was 48° C . and the mix appeared as a clear orange liquid. Seven minutes later $\frac{3}{4}$ of the CS_2 had been added. The pot temperature was 54° C . and the mix was a cloudy orange liquid. The addition of CS_2 was completed ten minutes later. The pot temperature was 57° C . and the mix was an orange slurry. The reaction was allowed to proceed for another ten minutes at which time the pot temperature was 54° C . At this point the dropwise addition of 126.5 gms. (1.0 mole) of benzyl chloride was begun. Two minutes later the addition was temporarily stopped because the reaction mix was too thick. The pot temperature at this time was 55° C . 100 ml. of H_2O was added to the mix to thin it out. This reduced the pot temperature to 44° C . The heater was turned on (40 v.) and the addition of benzyl chloride was continued. Twenty-five minutes after the addition of benzyl chloride was continued $\frac{2}{3}$ of the benzyl chloride had been added. The pot temperature was 67° C . and the reaction mix appeared as a thin, yellow, cloudy liquid. The addition of the ben-

EXAMPLE 4

Dibutyltin bis (N-butyl-S'-benzyl isodithiocarbamate)

zyl chloride was completed 25 minutes later at which time the pot temperature was 92° C. The reaction mixture now appeared as two liquid layers. The bottom layer is a light brown oil and the top layer is

The mix was heated for another 30 minutes and the heat was turned off to cool the mixture. The mix was allowed to stand overnight. The next day the bottom oily layer had become rather viscous. On pouring into a separatory funnel, the oily layer turned into a yellow solid. The water was poured off and the solid was dissolved in toluene. This was allowed to stand till the next day. As much H₂O as possible was removed from the toluene solution. The remainder was poured into a clean 2 liter flask and 124.4 gms. (0.5 mole) of dibutyltin oxide was added. The flask was placed in the set up and the heater and stirrer were turned on. The reaction was allowed to proceed for one hour and 40 minutes at which time the oxide had dissolved and the pot temperature was 107° C. The reaction was continued for another three hours and then the heater and stirrer were turned off. The reaction mix was allowed to stand overnight. The next day some solid crystalline material was present which was separated by filtration under suction. Dry weight was 48.3 and was labelled A.

The filtrate was stripped by jet water vacuum distillation yielding a light brown liquid labelled B.

Analysis of A:

Sn=0.99%

Sulfur (comb.)=13.19%

Analysis of B:

Sn=19.06%

Sulfur (comb.)=16.19%

Theoretical:

Sn=15.6%

S=16.8%

The reaction sequence may be described by the following:

5

Using the same apparatus described in Example 1, a mixture of 73 gm. (1.0 mole) of BuNH₂ and 40.9 gm. (Bakers, pellets 98.2%) (1.0 mole) of NaOH in 250 ml. of H₂O was charged in the flask. 76 gm. (1.0 mole) of CS₂ was added dropwise to the flask. The temperature of the mix in flask was 20° C. and the stirrer was turned on. The addition of the CS₂ was completed in 10 min. The temperature of the reaction mix rose to approximately 70–80° C. The mix appeared as a deep orange red nearly clear solution. Five minutes after completion of the addition of CS₂, 126.5 gm. (1.0 mole) of benzyl chloride was added to the reaction mix. Addition of benzyl chloride was completed in about 7 minutes. At this time a yellow oil separated from a lower colorless aqueous layer in the reaction flask. The temperature at this time was 90–95° C. approximately. The reaction continued and 13 minutes later the temperature was 78° C. Ten minutes after this, 200 ml. of benzene was added. The oil layer dissolved in the benzene. The temperature of the mix at this time was 60° C. Ten minutes after the addition of the benzene, the lower layer was siphoned off. The benzene layer was washed with 100 ml. of distilled H₂O. 15 minutes later with a Barrett water separator in the system the heater and stirrer were turned on. Nine minutes later the pot temperature was 73° C. and water was distilling. The water was separated off. The reaction was continued for another 4 hours and 8 minutes at the end of which time the pot temperature was 90° C. and all of the H₂O had come over. The reaction mix was then allowed to cool. Seven minutes later the pot temperature was 40° C. and 124.4 gms. (0.5 mole) of Bu₂SnO was added. The heater and stirrer were turned on. 21 minutes later the pot temperature was 80° C. and 2+ ml. of H₂O had come over. 36 minutes later the pot temperature was 95° C. and the oxide had been completely dissolved. 7+ ml. of H₂O had come over. The reaction was continued for another 17 minutes and then the heat was turned off. The reaction mix was allowed to stand about 5 days. The mix was then stripped using a downward vacuum stripping assembly. This was done in 2 hours and 10 minutes. The final temperature was 100° C. Most of the benzene had come out of the product. The residue was bottled (wt. 322.3 gm.).

Analysis:

The reaction sequence may be described by the following:

The hydrocarbon tin isodithiocarbamates of the present

invention are useful as stabilizers for vinyl resins, as ingredients of rubber compositions functioning as curing accelerators, and/or antiozonants and/or antioxidants.

The following examples are illustrative of the usefulness of the hydrocarbontin isodithiocarbamates of the present invention.

Use as vinyl resin stabilizer

The hydrocarbontin isodithiocarbamates of the present invention are useful as stabilizers for vinyl resins, particularly chlorine-containing vinyl resins such as polyvinyl chloride, polymeric vinylidene chloride, copolymers of vinyl chloride and styrene and copolymers of vinyl chloride with vinyl acetate. In connection with vinyl resins, it has been found that the hydrocarbontin isodithiocarbamates of the character described when added to the vinyl resin in amounts equal to 0.5 to 10.0 parts by weight of stabilizer to 100 parts of resin are effective as stabilizers. However, for commercial use, 1.0 to 3.0 parts by weight of stabilizer to 100 parts by weight resin is preferred.

A general test method was used to test the effectiveness of the products of this invention as stabilizers for polyvinyl chloride resins. The resin used was Geon 101 (produced by B. F. Goodrich Co.) unless otherwise specified.

The stabilizer was incorporated into a mixture of 100 parts by weight of resin and 50 parts by weight of a plasticizer (here Flexal DOP (dioctyl phthalate)). The weight of stabilizer was determined by its analysis. Thus enough stabilizer was used to provide 0.374 part by weight of Sn. This was done in order to determine the relative merits of the various compounds.

The mixture was then milled for 5 minutes on a two-roll differential speed mill heated to 320-325° F. and removed as a sheet. Portions of the sheet were then placed in a single cavity mold (6" x 6" x 40 mills) preheated to 275° F. The mold was placed on a press and raised to 320° F. under 10,000 pounds total pressure. When the mold reached 320° F. the pressure was increased to 40,000 pounds and held until the temperature reached 330° F. This procedure required 5 to 5½ minutes. The mold and press platens were then cooled and the pressed sheet removed.

The pressed sheet was cut into 1" x 6" strips and placed in clips on a tray so that the strips would hang vertically. The tray was then placed in a circulating air oven held at 320° C. Samples were removed after one hour, two hours, three hours and four hours of heat aging. Samples were rated visually. Summary of tests are indicated as follows:

Summary table

Code: 1, dark amber; 2, light amber; 3, tan; 4, yellow; 5, pale yellow; 6, faint yellow; 7, colorless.

APPEARANCE AFTER HEAT AGING

Stabilizer from Example No.	0 hr.	1 hr.	2 hrs.	3 hrs.	4 hrs.
No stabilizer	1	1			
Example 1	6	5	5	4	3
Example 3	6	4	4	4	3
Example 4	6	5	5	3	3

Use as antiozonant and antioxidant

The hydrocarbon isodithiocarbamates of the present invention are also very effective antioxidants and antiozonants for rubbery material, e.g., GRS rubber, neoprene and natural rubber. They protect rubbery compounds from cracking due to sunlight exposure under dy-

namic or static exposure. They also improve heat resistance and retard discoloration of rubber compositions containing them. Of particular interest in this regard is the following compound:

1. Triphenyl tin S(N-cyclohexyl-S'-cyclohexyl isodithiocarbamate).

The organotin isodithiocarbamates of this invention are effective as antioxidants and antiozonants in the range of 0.1 to 3.0 parts of stabilizer per 100 parts of rubbery compound.

While the invention has been described with particular reference to specific embodiments, it is to be understood that it is not limited thereto but is to be construed broadly and restricted solely by the scope of the appended claims.

What is claimed is:

1. Organotin isodithiocarbamates of general formula:

wherein n is an integer from 1 to 3 inclusive, a is an integer from 0 to 2 inclusive, the sum of $n+a$ being not greater than 3 and R , R' , R'' and R''' are hydrocarbon radicals.

2. Organotin isodithiocarbamates of general formula:

wherein n is an integer from 1 to 3, and R' , R'' and R''' are hydrocarbon radicals.

3. Organotin isodithiocarbamates according to claim 2 wherein R' , R'' and R''' are selected from the class consisting of alkyl, aryl, aralkyl and cycloalkyl radicals.

4. A process for the preparation of hydrocarbontin isodithiocarbamates which comprises reacting and isodithiocarbamic acid of formula

- 45 with an organotin compound selected from the class consisting of hydrocarbontin halides and hydrocarbontin oxides, wherein R' and R'' are hydrocarbon groups.

5. A process for the preparation of a hydrocarbontin isodithiocarbamate of claim 1 which comprises reacting a primary amine with CS_2 and an alkali metal hydroxide to form the corresponding alkali metal salt of a dithiocarbamic acid, reacting said salt with a hydrocarbon halide to form the corresponding isodithiocarbamic acid 55 and then reacting the isodithiocarbamic acid with a hydrocarbontin compound selected from the group consisting of hydrocarbontin halides and hydrocarbontin oxides to produce the corresponding hydrocarbontin isodithiocarbamate.

60. 6. Dimethyltin bis S(N-butyl S'-benzyl isodithiocarbamate).

7. Dimethyltin bis S(N-benzyl-S'-benzyl isodithiocarbamate).

8. Dimethyltin bis S(N-cyclohexyl-S'-benzyl isodithiocarbamate).

- 65 9. Dimethyltin bis S(N-butyl-S'-benzyl isodithiocarbamate).

10. A process according to claim 5 wherein said primary amine is butylamine, said hydrocarbon halide is 70 benzyl chloride and said hydrocarbontin compound is dimethyltin oxide.

11. A process according to claim 5 wherein said primary amine is benzylamine, said hydrocarbon halide is benzyl chloride and said hydrocarbontin compound is 75 dimethyltin oxide.

12. A process according to claim 5 wherein said primary amine is cyclohexylamine, said hydrocarbon halide is benzyl chloride and said hydrocarbontin compound is dibutyltin oxide.

13. A process according to claim 5 wherein said primary amine is butyl amine, said hydrocarbontin halide is benzyl chloride and said hydrocarbontin compound is dibutyltin oxide. 5
